UNITED STATES PATENT OFFICE

135,008

DESIGN FOR A COMBINE

Charles E. Everett, Racine, Wis., assignor to The
Massey-Harris Company, Racine, Wis., a company of Maryland

Application November 3, 1941, Serial No. 104,005

Term of patent 14 years

To all whom it may concern:

Be it known that I, Charles E. Everett, a citizen of the United States, residing at Racine, in the county of Racine and State of Wisconsin, have invented a new, original, and ornamental Design for a Combine, of which the following is a specification, reference being had to the accompanying drawings, forming a part thereof.

Figure 1 is a side elevational view of a combine showing my new design.

Figure 2 is a front elevation view of the combine shown in Figure 1.

Fig. 3 is an elevational view of the side opposite to that shown in Fig. 1; and

Fig. 4 is a rear elevational view thereof.

The characteristic features of my design are shown in full lines.

I claim:

The ornamental design for a combine, as shown and described.

CHARLES E. EVERETT.
